UNITED STATES PATENT OFFICE.

POWELL EVANS, OF PHILADELPHIA, PENNSYLVANIA, ASSIGNOR, BY MESNE ASSIGNMENTS, TO GLOBE AUTOMATIC SPRINKLER COMPANY, OF PHILADELPHIA, PENNSYLVANIA, A CORPORATION OF PENNSYLVANIA.

DRY-PIPE VALVE.

1,226,488.

Specification of Letters Patent. Patented May 15, 1917.

Application filed December 11, 1913. Serial No. 805,999.

To all whom it may concern:

Be it known that I, POWELL EVANS, a citizen of the United States, residing in Philadelphia, Pennsylvania, have invented 5 certain improvements in Dry-Pipe Valves, of which the following is a specification.

One object of this invention is to provide a relatively simple and substantial form of dry pipe valve for use in fire extinguishing systems, whose construction shall be such as to render its operation certain when the pressure in the air containing portion of the system is reduced to a predetermined point, the parts being so constructed and disposed 15 as to permit of the valves and their connecting mechanism being reset, after the apparatus has operated, with the utmost ease and certainty.

A further object of the invention is to 20 provide a novel, reliable and substantial dry pipe valve of the type in which a weighted element outside of the main casing is operatively connected to the mechanism within the same, which shall embody a chain of 25 members operatively connecting the two valves or clappers and including one member automatically adjustable to compensate for wear, lost motion or irregularities of construction.

30 These objects and other advantageous ends I secure as hereinafter set forth, reference being had to the accompanying drawings, in which:—

Figure 1 is a vertical section of a dry pipe 35 valve constructed according to my invention and illustrating the various parts in their set positions;

Fig. 2 is a vertical section similar to Fig. 1, illustrating the parts in the positions occupied after the valve has operated;

Figs. 3 and 4 are vertical sections of modified forms of my invention;

Figs. 5 and 6 are respectively a side and a 45 rear elevation of certain detail parts of one form of the invention;

Fig. 7 is a perspective view of another part;

Figs. 8 and 9 are vertical sections showing another form of my invention in its set and 50 open positions respectively, and

Fig. 10 is a vertical section on the line $a-a$ Fig. 8.

In Figs. 1 and 2 of the above drawings, 1 represents a suitably formed casing having

a transverse partition 2 which divides it into 55 an air chamber 3 and an intermediate chamber 4, there being a fitting 5 connected to an opening in the bottom of said intermediate chamber and communicating with a suitable source of water under relatively high pressure. The casing 1 also has a flanged outlet opening 6 from the top of the air chamber and has a side opening from the same chamber, which is normally closed by a plate or a hinged door (not shown). The intermediate 60 chamber 4 likewise has a side opening also normally closed by any suitable means.

Confined between the fitting 5 and the shoulder of an annular recess concentric with the opening into the chamber 4, is a 70 ring 11 serving to clamp an annular diaphragm 12 between its upper edge and said shoulder, and this diaphragm at its center carries a second ring or sleeve 13 constituting a seat for the water valve 15. This ring, 75 by reason of the resilient support provided by the diaphragm, provides a more or less yielding structure for co-action with the water valve or clapper and serves as an automatically adjustable element which takes up 80 any wear or lost motion in the chain of valve-connecting members hereafter described.

The valve 15 consists of a disk-like structure having in its lower face an annular 85 packing of metal or other suitable material designed to make a tight joint with the seat 13, and having projecting from its top surface a pair of hinge members 16 pivoted to the casing structure by a pin 17. At the 90 center of its top face is inserted a buffer 18 designed to prevent shock or injury when it is violently turned on its pivot pin 17 and caused to strike the casing, which is provided with a projecting lug 19 for co-action with the buffer. This latter may be made of any desired and suitable material such as rubber or soft material.

The side of the valve opposite that having the hinge lugs 16 has a projecting stop in 100 the form of an adjustable stud 21 and said valve is also designed to co-operate with a tumbler 22, rotatably mounted on a lever 23, which is pivoted by a transverse pin or spindle 24 to the casing structure 1.

This lever 23 also carries two stops 25 and 26, of which the first cooperates with the upper part of the tumbler 22 to limit its move-

ment on its pivot, while the second co-acts with the stud 21 of the valve 15 to limit the movement of the lever toward the same. Said lever is formed of two parallel and 5 preferably integral arms whose upper ends are connected by a pin or spindle 27 on which is hinged an arm 28 carrying a weight 29 on its outer end.

This arm projects through an opening in 10 one side of the casing 1 and immediately adjacent its hinge pin 27 is laterally extended to form a valve 30, which under certain conditions fits a suitably formed seat 31 mounted in this opening, and before it seats, may 15 also engage a part of the lever 23 to move the same. The weight 29 is preferably a metallic casting of suitable mass retained on the extremity of the arm 28 by a nut 32 and provided with an insert 33 of suitable 20 material to form a buffer at that point where under operating conditions it strikes the outside of the casing 1. The arm 28 adjacent the bearing for the pivot pin 27 has a lug 34 so placed and formed as to coöperate 25 with a trigger 35 pivoted by a pin 36 to an air-controlled device in the form of a controlling valve 37 which normally closes an opening through the partition 2, and is movably connected to said partition by a hinge 30 or pivot pin 38.

Said valve is prevented from rising more than a relatively short predetermined distance from its seat, and is also prevented from reseating automatically after it has 35 once risen, by a hooked arm 39, preferably fixed to or formed as part of the trigger 35 and designed to engage a pin 40 carried by a downwardly projecting lug 41, when the valve has opened to a predetermined extent. 40 The trigger 35 has an extension 42 operating in a slot formed in a projection 43 from the under face of the controlling valve 37, the arrangement being such that said trigger and the hooked arm 39 have a relatively 45 slight movement on the pivot pin 36 which is merely sufficient to permit of the raising of the trigger when the lug 34 of the arm 28 passes under it into its set position, without opening the controlling valve 37. The 50 upper end of the lever 23 has extensions 10 which limit the upward movement of the arm 28 on its pivot pin 27 while the movement of said arm in the opposite direction is limited by the engagement of the valve 55 30 with said lever.

The main air valve 44 of the apparatus is also hinged or pivoted to the partition 2 by the pin 38 and coöperates with a seat 8 mounted in a second opening of said partition 60 to one side of the vertical line through the seat 13 carried by the diaphragm 12, being provided with a suitable buffer 45 at that point thereof where it comes into engagement with the projecting lug 9 at one 65 side of the casing 1, when in its fully opened

position. The weighted end of the arm 28 is preferably inclosed by a suitably formed auxiliary casing 46 hinged to the main casing 1 at 47, and preferably provided at its lower end with a slotted lug 48 designed to receive a perforated hasp-like lug 49 engaged by a lock 59.

The various parts are so designed and constructed that when it is desired to set the apparatus, the door or plates closing the two chambers 3 and 4 is opened, after which the valves or clappers 15 and 44 may be placed in their closed positions upon the seat with which they co-act, the controlling valve 37 being at all times in engagement with its seat, except under conditions hereafter noted. The chambers 3 and 4 being then closed, air from any suitable source is admitted to the sprinkler system and to the first of said chambers. By opening the auxiliary casing 46 the weight 29 and with it the arm 28 may be raised and pushed inwardly from the position shown in Fig. 2 to that shown in Fig. 1, thus moving the double lever 23 on its pivot pin 24 toward the clapper 15. The inward movement of these parts is limited by the engagement of the stop 26 with the stud 21, although before this condition exists the lug 34 on the arm 28 passes under the hooked end of the trigger 35, which temporarily turns on its pivot pin 36 to allow such passage.

If the controlling valve 37 should be held open by reason of the engagement of the hooked arm 39 with the pin 40, this movement of the trigger would free these parts, allowing said valve to close. At the same time the projecting part 20 of the clapper 15 engages the tumbler 22 and it is to be noted that the point of this engagement is 105 slightly to the right side of the line connecting the centers of the pivot 24 and of the pin upon which the tumbler 22 is mounted. The weight 29 may now be released, whereupon the various parts remain in the 110 positions shown in Fig. 1, since the lever 23 under these conditions serves as a fixed supporting structure for arm 28 whose projecting lug 34 engages the hooked end of the trigger 35, so as to tend to cause opening of the controlling valve 37, under the action of 115 said weight.

Moreover, the various parts are so designed that when in their set positions the water valve 15 tightly engages and closely 120 fits its yieldingly mounted seat ring 13, though it deflects the diaphragm 12 to a greater or less extent, depending upon the adjustment and the amount of lost motion and wear between the various parts. Water 125 under pressure may now be admitted to the piping system in connection with the fitting 5, since with a predetermined air pressure in the sprinkler system, say of ten pounds to the square inch the force exerted on the 130

controlling valve 37 is sufficient to maintain it closed against the opening force exerted by the weight 29, plus that exerted by the water acting on the valve 15 and transmitted through the tumbler 22, the lever 23 and the lug 34.

When the air pressure in the chamber 3 falls to a predetermined point, as, for example, when one of the sprinklers of the system is opened (or an accidental leakage occurs), the combined force above noted causes the controlling valve 37 to slightly open by turning on its pivot pin 38, although the amount of this opening is just sufficient to permit of the lug 34 passing out of engagement with the hooked end of the trigger 35;—further opening of the valve being stopped because the hooked end of the arm 39 drops into engagement with the pin 40 (as shown in Fig. 2). This raising of the controlling valve, however, allows the arm 28 with its weight 29, to turn on the pin 27 as a pivot until the lower part of the valve 30 strikes the lever 23 and exerts thereon a force tending to move it on its pivot pin 24, away from the valve 15. Such movement permits the projecting end 20 to clear the tumbler 22, leaving the valve 15 free to move to its fully opened position, whereupon the water from the supply system enters the intermediate chamber 4 and, after opening the valve 44, passes into the air chamber 3 and thence into the sprinkler system.

The continued movement of the lever 23 with the arm 28 permits the valve 30 to seat itself on the ring 31 and thus prevents escape of water through the same opening for said arm and under these conditions the parts of the device occupy the positions shown in Fig. 2.

Upon the cessation of the water flow through the apparatus, the parts may be set as previously described, there being provided a drip outlet opening 50 in the lower part of the casing 1 to permit of the escape of water therefrom before the opening of the main door or removal of the cover plates. I also provide an opening 51 into the intermediate chamber, for reception of the pipe leading to an alarm valve and in the chamber 3 provide an opening 52 connected to a source of supply of air under pressure.

In that form of my invention shown in Fig. 3, I employ but a single valve 44^a in the partition 2^a between the intermediate chamber 4^a and the air chamber 3^a, making this serve the functions of the main air valve 44, as well as those of the controlling valve 37. For this purpose I mount on its under side a trigger 35^a having limited pivotal movement and designed to engage a lug 34 on a weighted arm 28^a in the same manner as described in connection with the apparatus shown in Figs. 1 and 2. The valve 44^a is preferably placed in the partition 2^a to

one side of the center line of the seat 13 for the water valve 15, which is held in its closed position by a chain of elements including a double lever 23^a, a tumbler 22^a and a weighted arm 28^a, similar except as to slight differences in form, to the corresponding parts in the other form of my invention. As before, the weight 29^a exerts an opening force on the valve 44^a and when the latter opens, turns on its pivot 27, thereafter acting on the lever 23^a to move it away from the water valve 15.

In the third form of my invention shown in Fig. 4, I control the opening of the water valve 15 by means of a flexible diaphragm 55 clamped by a ring 56 in a suitable opening in the partition 2^b between the intermediate and air chambers of the casing 1^b. In this case I provide a main air valve 44^b similar to the valve 44 Fig. 1, and pivot to the central portion of the diaphragm 55 a trigger 35^b, whose movement on its pivot pin is limited by a slotted arm 43^b. When the apparatus is set, said trigger engages a lug 34^b on the arm 28^b in a manner practically identical with that heretofore described.

Ordinarily the air pressure in the chamber 3^b maintains the air-controlled device formed by the diaphragm 55 in such position that its trigger 35^b, through the lug 34^b, holds the weighted arm 28^b in its raised position and maintains the double lever 23 in such a position as to cause the tumbler 22 to hold the water valve 15 closed. When, however, the air pressure in this chamber falls below the predetermined point, the diaphragm deflects sufficiently to withdraw the trigger 35^b from engagement with the lug 34^b, whereupon the weight 29^b falls with the arm 28^b which causes such movement of the lever 23 as allows the water valve to open. Thereafter the water passing into the chamber 4^b opens the air valve 44^b and flows thence into the sprinkler system.

In this case as in the others described, the parts are so designed as to permit of their rapid and easy setting after the two clappers have been closed, it being only necessary to raise the weight 29^b and move the arm 28^b into the casing, whereupon the lug 34^b passes under the trigger 35^b and the tumbler 22 engages the clapper 15, so that as soon as the air pressure is admitted to the chamber 3^b, said clapper is held closed.

In that form of my invention shown in Figs. 8, 9 and 10, I have illustrated a relatively simple arrangement of parts, which like that of Fig. 3, includes a yieldingly mounted seat 13^c for the water valve 15^c, together with a tumbler 22^c mounted so as to have limited rotation on a double lever 23^c pivoted to the casing 1^c at 24^c and hinged to an arm 28^c by a pivot pin 27^c. This arm carries an elongated weight 29^c and is provided adjacent its pivot 27^c with

a projection 34° placed to detachably engage a trigger 35° so connected to the air-controlled device provided by the valve 44° as to have a limited pivotal movement thercon. This air valve is hinged or pivoted to the partition 2° between the air chamber 3° and the intermediate chamber 4° by means of a pin or pintle 34° though in this instance the weighted arm 28° is wholly within this intermediate chamber and the main casing 1° is so constructed that the auxiliary casing 46° provides an extension in which said arm operates. Said casing is pivoted or hinged to the main casing by a hinge structure 47°.

Under conditions of operation, the various parts behave as previously described in connection with that form of my invention shown in Fig. 3, the weighted arm 28° when 20 allowed to fall by the raising of the valve 44° and trigger 35°, turning downwardly until it engages the lever 23° which it thereafter turns on its pivot 24° away from the water valve 15°. This latter is thus cleared 25 by the tumbler 22° and is free to open under the water pressure acting in the fitting 5 and valve seat 13°, so that the water flows through the intermediate chamber 4° and the outlet 6. Under these conditions the 30 various parts occupy the positions shown in Fig. 9.

As before, in setting the apparatus, after the casing 46° is opened, the water and air valves may be moved to their closed positions, it being necessary to remove a cover plate 60. Thereafter the hooked end of the weighted arm 28° may be caused to pass under the trigger 35° until the stop 26° engages the water valve, whereupon said 40 arm may be released, thus leaving the parts in the set positions shown in Fig. 8. In this instance, as well as in the others previously described, the tumbler 22° is kept by its stop 25° from moving out of its pre- 45 determined position so that it is necessarily engaged in the proper manner by the water valve 15°.

It is to be understood that the design and proportions of the various levers and 50 the placing of their pivots will be determined by the particular pressures of air and water employed in the systems of which the apparatus forms a part, and may be widely varied without departing from 55 my invention.

It is to be particularly noted, however, that the yielding support for the seat ring 13 provided by the diaphragm 12, permits the water valve 15 to make a tight joint 60 with said ring in spite of slight inaccuracies in the dimensions or in the engagement of the various co-acting parts above described, so that leakage is effectively prevented.

65 It is further noted that the stop 26, by

engaging the stud 21 of the valve 15 when the parts are being set, insures the lever 23 being so positioned that the projection 34 of the arm 28 may be conveniently and certainly brought into and held in the proper position to engage the hooked end of the trigger 35 when the valve 37 is closed; it being thus possible to set the parts in a short time and yet without possibility of their being engaged in other 75 than the proper operative positions.

One of the important features of the invention resides in the peculiar construction and combination of the lever 23 and weighted arm 28, for it will be noted that the latter under normal conditions acts through its projection 34, merely as a lever fulcrumed on the pivot pin 27 and exerting an opening force on the valve 34. When, however, the trigger has disengaged said projection and the weighted arm has fallen so that its valve 30 or other suitable part engages the lever 23, said arm acts as a rotating means to move said lever out of operative connection with the valve 15 and into a position to one side of the clear water way through the valve, finally occupying a position, in the case shown in Figs. 1 to 7, in which said valve 30 closes the opening in the casing.

I claim:

1. The combination in a dry pipe valve of a casing; a water valve; an air-controlled device; and mechanism operatively connecting said valve and said device including a lever having a member normally holding the valve shut; and a weighted arm projecting outside the casing and mounted on the lever in position to be operative on the air-controlled device to move the same; with a part integral with said weighted arm for closing the opening in the casing under predetermined conditions.

2. The combination in a dry pipe valve of a water valve; an air-controlled device; and mechanism operatively connecting said valve and said device including a lever having a member normally holding the valve shut; a weighted arm mounted on the lever and operative on the air-controlled device to tend to move the same independently of the valve and said lever; with means for causing said weighted arm to engage and turn the lever on its pivot under predetermined conditions.

3. The combination in a dry pipe valve of a yielding supported valve; an air-controlled device; and mechanism connecting said valve and device including a lever operative on the valve to keep it shut; said mechanism including a weighted arm mounted on said lever; with a member mounted on the air-controlled device and normally engaged by said weighted arm.

4. The combination in a dry pipe valve

- of a water valve; an air-controlled device; and mechanism operatively connecting said valve and said device, the same including a lever normally holding the water valve shut; 5 with a weighted arm fulcrumed on said lever and operative on said valve, said arm having a projection placed to engage and turn the lever on its pivot under predetermined conditions.
- 10 5. The combination in a dry pipe valve of a water valve; a stud adjustably threaded into the top portion of said valve; an air controlled device; mechanism operatively connecting said valve and said device including a lever having a structure placed to detachably engage the water valve; a member connected to said lever and operative on the air controlled device; with a stop on the lever above its valve-engaging 15 structure in position to engage the stud on the water valve to limit the movement of said lever toward said valve.
6. The combination in a dry pipe valve of a water valve; an air-controlled device; 20 and mechanism operatively connecting said valve and said device, the same including a lever fulcrumed at one side of the water valve and having a rotatable tumbler engaging the same to keep it shut; with a weighted arm fulcrumed to the free end of 25 the lever and detachably operative on the air-controlled device.
7. The combination in a dry pipe valve of a casing structure; a water valve; an air-controlled device; and mechanism connecting said valve and said device, the same including a member movably mounted adjacent the water valve; an element rotatably mounted on said member and having two 30 eccentric portions of which one is placed to act on the water valve to keep it shut; with a stop on said member placed to engage the second eccentric portion of said element to limit the rotary movement thereof.
- 45 8. The combination in a dry pipe valve of a water valve; an air-controlled device; a lever mounted adjacent the water valve; a tumbler rotatably mounted on the lever and operative on the water valve; and a weighted member mounted on the lever and 50 operative on the air-controlled device.
9. The combination in a dry pipe valve of a casing; water, air and controlling valves respectively within said casing; mechanism 55 connecting the water valve and the controlling valve, including a weighted member pivoted in but extending outside of, the casing through an opening therein; with a fourth valve for closing said opening under 60 operating conditions.
10. The combination in a dry pipe valve of a casing; a water valve, an air valve and a controlling valve mounted therein; mechanism connecting the water valve and the 65 controlling valve, and including a lever nor-
- mally operative to hold the water valve shut; with a member fulcrumed on said lever and tending to open the controlling valve, said member having a portion extending through an opening in the casing and being provided 70 with a valve for closing said opening when the water valve is open.
11. The combination in a dry pipe valve of a casing; a water valve, an air valve, and a controlling valve mounted therein; mechanism 75 connecting the water valve and the controlling valve, the same including a lever for normally holding the water valve shut; a second lever fulcrumed on the first lever and extending through an opening in the 80 casing; a trigger mounted on the controlling valve and engaged by said second lever; a weight fixed to the second lever outside of the casing; and a valve carried by said second lever for closing the opening when the 85 water valve is open.
12. The combination in a dry pipe valve of a casing; a water valve; and air controlled means for normally holding said water valve closed; the same including a 90 valve movable when the air pressure falls below a predetermined point; means for holding said valve from more than a limited opening; a trigger pivoted to said valve and supporting said means; and a device 95 normally held by the trigger in position to maintain the water valve closed.
13. The combination in a dry pipe valve of a water valve; an air valve; mechanism operatively connecting said valves, the same 100 including a lever having means operative to hold the water valve shut; a weighted lever projecting through an opening in the casing and fulcrumed to the first lever; a valve on the weighted lever for closing the opening 105 and formed to engage the first lever to move the same before seating; and air-controlled means acting on said parts to normally maintain the water valve closed.
14. The combination in a dry pipe valve 110 of a casing; a water valve therein; a device movable when the air pressure in the casing falls below a predetermined point; and means for connecting said device to the water valve to normally hold the latter shut, 115 the same including a lever; a rotary tumbler mounted on said lever in position to engage the water valve; and two stops on the lever respectively in positions to engage the tumbler and to limit movement of the lever toward 120 the water valve.
15. The combination in a dry pipe valve of a casing; a water valve therein; and air-controlled means for normally holding the water valve closed, the same including a 125 lever having means operative on the water valve; a weighted lever hinged to the first lever; and means for limiting the movement of said weighted lever on the first lever.
16. The combination in a dry pipe valve 130

of an air controlled device; a water valve; mechanism connecting said parts and including a weighted member tending to move the air controlled device; with a second member normally holding the valve closed and carrying said weighted member so as to be positively moved thereby upon the release of the air controlled device.

17. The combination in a dry pipe valve of a casing; a water valve therein; a device movable when the air pressure in the casing falls below a predetermined point; and means for connecting said device to the water valve to normally hold it shut, the same including a lever; a cam-shaped structure rotatably mounted on said lever and having two shoulders of which one is placed to engage the water valve, and means placed to engage the second shoulder of said structure to limit the rotation thereof.

18. The combination in a dry pipe valve of a casing structure; a water valve; an air controlled device; and mechanism operatively connecting said valve and said device, the same including a member pivoted to the casing structure; a tumbler consisting of a structure having a shoulder and rotatably mounted on said member; with a stop on the lever placed to engage the shoulder for limiting the rotary movement of the tumbler; and a second stop for limiting the movement of the lever toward the valve.

19. The combination in a dry pipe valve of water, air and controlling valves; mecha-

nism connecting the water valve and the controlling valve; with means for limiting the movement of the controlling valve consisting of a hook connected thereto; and a stud placed to be engaged by the hook when the valve is moved a predetermined distance off its seat.

20. The combination in a dry pipe valve of water, air and controlling valves; mechanism connecting the water valve and controlling valve for normally holding the former closed; a stud; with a structure connected to the controlling valve and operative on the stud for preventing said valve rising more than a predetermined distance from its seat.

21. The combination in a dry pipe valve of a casing having a valve seated opening, an inlet and an outlet; a water valve for closing the inlet; a controlling valve; and mechanism for operatively connecting said controlling valve and the water valve, the same including a pivotally mounted arm extending through the valve seated opening; a valve on said arm for closing the opening; and a weight mounted on the arm outside of the casing.

In testimony whereof, I have signed my name to this specification, in the presence of two subscribing witnesses.

POWELL EVANS.
